ABSTRACT OF THE DISCLOSURE

A material handling machine includes a boom member pivotally carried on a boom support for movement about a boom pivot axis in a vertical plane. A link member is pivotally carried on the boom at a location below the boom pivot axis. A hydraulic lift means is pivotally connected to the link member and when actuated effects pivoting movement of the boom about the boom pivot axis. A power means acts between the boom support and the link member to effect pivotal movement of the link member relative to the boom pivot axis.

The present application is a divisional of United States application Ser. No. 540,014, filed Apr. 4, 1966, now Patent No. 3,392,855 and assigned to the assignee of the present invention.

The present invention relates to a material handling machine, and particularly relates to a material handling machine, such as a backhoe, which includes a boom member having a dipper stick pivotally connected to the end of the boom member, and wherein the boom member is pivotally connected to a support for pivotal movement about a horizontal axis and power means which acts between the boom and the support for effecting vertical pivotal movement of the boom.

Known material handling machines, such as a backhoe, include a boom carried by a support for pivotal movement in a substantially vertical plane about a horizontal axis. The vertical movement or stroke of the boom about the horizontal pivot axis is effected by a power means. The power means moves the boom at a particular speed and power providing a boom stroke having a particular speed-power relationship. Preferably, in known material handling machines, the power means includes a hydraulic cylinder and piston rod. The hydraulic cylinder is generally connected for pivotal movement about a horizontal axis to the support and the outer end of the piston rod is generally pivotally connected to the boom so as to provide for the necessary relative movements between the piston rod and boom, on the one hand, and the hydraulic cylinder and support, on the other hand, as the boom moves vertically about the horizontal pivot axis.

The boom generally carries on its outermost end a dipper stick equipped with a suitable tool for performing some operation. Commonly, the tool is a bucket for effecting digging or movement of some material. These machines, however, are effective to perform numerous different operations, depending upon the use of the tool supported on the end of the boom, and may be capable of lifting and/or carrying heavy loads. Due to the various uses for these machines, the lifting and/or digging power requirements for the boom vary. Moreover, the desired speed of vertical movement of the boom also varies.

In accordance with the present invention, there is provided a new and improved material handling machine having a boom carrying a dipper stick and wherein the boom is movable in a vertical plane by a power means and wherein the speed-power relationship for boom movement may be controlled and varied within limits. This

2

provides for rapid boom movement when handling light loads requiring little power, and also provides for handling heavy loads requiring greater power but at a low speed. The ability to vary the speed-power relationship does provide a material handling machine of greater versatility and efficiency.

Accordingly, the principal object of the present invention is the provision of a new and improved material handling machine having a boom carrying a dipper stick and wherein the boom is pivotal about a horizontal axis by power means and which is constructed and arranged so that the speed-power relationship for boom movement may be controlled through a wide range whereby the boom may be readily moved either through a power stroke at a relatively low rate of speed or through a speed stroke at a relatively high rate of speed but at less power.

A still further object of the present invention is the provision of a new and improved material handling machine incorporating a boom supported for pivotal movement about a horizontal axis relative to a support frame and a hydraulic lift mechanism operatively connected to effect the vertical movement of the boom and wherein the lift cylinder is connected to a link member which, in turn, is pivotally connected to the boom and wherein a hydraulic cylinder acts between the link and support frame and when energized moves the link member so as to vary the relative position of the boom pivot and the connection of the piston rod relative to the boom thereby varying the effective force applied by the hydraulic mechanism to effect movement of the boom.

Further objects and advantages of the present invention will be apparent to those skilled in the art to which it relates from the following detailed description of the preferred embodiment thereof made with reference to the accompanying drawings forming a part of this specification and in which:

FIG. 1 is a schematic perspective view of a material handling machine embodying the present invention;

FIG. 2 is a detailed view of a portion of the material handling machine shown in FIG. 1;

FIG. 3 is a view illustrating schematically the mechanism shown in FIG. 2; and

FIG. 4 is a sectional view taken approximately along section line 4—4 of FIG. 2.

The present invention provides an improved material handling machine having a boom movable in a vertical plane about a substantially horizontal axis and wherein the movement of the boom is effected by a power means. The present invention is adapted for use in any type of material handling machine which incorporates such a boom and is particularly adapted for use in material handling machines which have varying demands with regard to speed of boom movement and power capability of the boom.

As representing the preferred embodiment of the present invention, FIG. 1 illustrates a material handling machine 10. The material handling machine 10 includes a support carrier 11 which carries a support platform 12. The support platform 12 is rotatable about a substantially vertical axis and carries a boom structure 13. The boom structure 13 is supported for pivotal movement about a horizontal axis 91 and is pivoted about the horizontal axis 91 by a power means 93.

The boom structure 13 includes a boom member 90 which is pivotally supported for movement about the axis 91 by pivot pin means which extends through a pair of spaced support frame members 92 secured to the platform 12. Upon actuation of the power means 93, the boom 90 moves relative to the support platform 12 and support frame members 92. The boom 90 on its outermost end carries a dipper stick 22 for pivotal movement relative to the boom 90. The dipper stick 22 may be pivoted about

a pivot axis 23 by a hydraulic cylinder 24. The outermost end of the dipper stick 22, of course, carries a suitable material handling implement, a digging bucket 26, as shown in the drawings and which is suitably actuated by a hydraulic power means (not shown) in a conventional manner.

The power means 93 for effecting vertical movement of the boom is preferably a hydraulic power means including a cylinder 94 and a piston rod 96 pivotally connected at its outer end to the boom 90 at a location below the pivot axis 91 for the boom 90. The piston rod 96 is pivotal relative to the boom about a pivot axis 97. The piston rod, when it moves, applies a force to the boom 90 to effect movement thereof.

In accordance with the present invention, the material handling machine 10 is constructed so that the speed-power relationship for boom movement can be varied. Thus, the boom 90 may be moved at different speeds and have different lifting capabilities. The speeds and power capabilities can be varied over a substantial range, and at one limit the boom can move through a speed stroke wherein the boom moves through a wide range of movement at a relatively fast speed, while at the other limit, the boom 90 moves through a power stroke wherein the boom moves through a lesser range of movement than in the speed stroke but is capable of handling greater loads.

During the speed stroke, the hydraulic mechanism 93 applies a given force to the boom to effect movement thereof about the pivot axis 91, whereas during the power stroke the hydraulic mechanism applies a greater effective force to the boom to effect movement of the boom about the pivot axis 91. In view of the fact that a greater effective force is applied to the boom for movement about the pivot axis, the boom is capable of handling greater loads during the power stroke.

The fact that the speed-power relationship for boom movement can be varied enables the material handling machine 10 to be utilized highly effectively and with a great flexibility. The boom is, of course, capable of moving at higher rates of speed through a wider range of movement, thereby enabling light loads to be handled relatively quickly and through a wide range of movement. The fact that the boom is capable of moving through a power stroke enables the mechanism to be utilized for digging in relative hard ground and more readily enables the material handling machine to be utilized for lifting heavier loads.

More specifically, the piston rod 96 is pivotally connected at 97 to a plate or link member 98 which, in turn, is pivotally connected at 99 to the boom 90. The link 98 is also pivotally connected at 97 to a piston rod 101 of a hydraulic cylinder 102. The hydraulic cylinder 102 is pivotally connected to the frame for pivotal movement about an axis 103 of a pivot pin 104 and which axis is spaced a slight distance from the boom pivot axis 91. The point 97 at which the lifting force is applied to the boom is located below the boom axis.

The hydraulic cylinder 102 and the link 98 comprise means for selecting whether the boom moves through a power stroke or a speed stroke. Specifically, when the cylinder 102 is in its de-energized condition and the parts are in the position shown schematically in full lines in FIG. 3, the boom, when moved about its pivot axis 91 is moved through a speed stroke through an angle of movement designated H in FIG. 3. However, when the cylinder 102 is energized and the link 98 is moved about its pivot 99, the point 97 at which the force is applied by the hydraulic mechanism 93 to the boom is moved away from the boom pivot point 91 and downwardly to the location designated 97a.

When the point 97 is moved to 97a, a lengthening of the lever arm for the boom lifting force occurs. The lever arm LS for the speed stroke is considerably shorter than the lever arm LP for the power stroke. Moreover,

the angle T which is the angle formed by a line indicating the force applied by the mechanism 93 and a line extending through the boom pivot axis 91 and the point of connection of the hydraulic mechanism 93 to the link 98 is less than the angle U which is formed between these

same lines during the speed stroke and is more nearly 90°. Thus, the effective force applied to the boom is substantially greater when the parts are in the power position. When in this position and the hydraulic mechanism is energized, the boom moves through a power stroke and through a range of movement, designated I in FIG. 3, which is substantially less than the range of movement designated H. Moreover, as shown in FIG. 3, the boom power stroke lies entirely within the range of movement of the speed stroke. Furthermore, the speed-power relationship can be varied within these limits so that the intermediate speed-power relationships are available by moving link 98 to a position intermediate its limit positions.

It should be apparent from the above that the preferred embodiment of the present invention has been described in considerable detail, but that certain modifications, changes, and adaptations may be made therein by those skilled in the art to which it relates.

25 What is claimed is:

1. A material handling machine comprising boom support means, a boom member carried by said boom support means, a pivotal interconnection between said boom member and said boom support means adjacent one end of said boom member and providing for pivotal movement of said boom member relative to said boom support means, power means acting between said boom member and said boom support means for effecting pivotal movement of said boom member relative to said boom support means, at least one link member and means supporting said link member on said boom member below the boom pivot axis for movement relative to said boom pivot axis, said power means having a pivotal interconnection with said link member movable relative to said boom pivot axis upon movement of said link member relative to said boom.

2. A material handling machine as defined in claim 1 wherein said means supporting said link member on said boom member supports said link member for pivotal movement relative to said boom member.

3. A material handling machine as defined in claim 1 further including additional power means for moving said link member relative to said boom member and acting between said link member and said support means.

4. A material handling machine as defined in claim 1 wherein said power means has a pivotal interconnection with said boom support means and is located below said pivotal interconnection of said boom member and said boom support means.

5. A material handling machine comprising boom support means, a boom member carried by said boom support means, a pivotal interconnection between said boom member and said boom support means adjacent one end of said boom member and providing for pivotal movement of said boom member relative to said boom support means, power means acting between said boom member and said boom support means for effecting pivotal movement of said boom member relative to said boom support means, at least one link member movably supported on said boom member for movement relative to said boom pivot axis, said power means having a pivotal interconnection with said link member movable relative to said boom pivot axis upon movement of said link member relative to said boom, and additional power means acting between said boom support means and said link member for effecting movement of said link member relative to said boom member.

6. A material handling machine as defined in claim 5 wherein said means supporting said link member on said

boom member supports said link member for pivotal movement relative to said boom member.

7. A material handling machine comprising a support, a boom carried by said support, means supporting said boom for pivotal movement relative to said support about a boom pivot axis, hydraulic power means acting between said boom and said support for selectively effecting pivotal movement of said boom about said boom pivot axis, said hydraulic power means comprising a hydraulic cylinder pivotally connected to said support and a piston rod pivotally associated with said boom at a point on the boom below said boom pivot axis, and means for selecting a power stroke or a speed stroke for said boom comprising additional power means acting on one of said pivotal connections for moving said one of said pivotal connections from a first position wherein said hydraulic power means applies a given effective force for moving said boom about said pivot axis and a second position wherein said hydraulic power means applies a greater effective force to said boom for moving said boom about said pivot axis.

8. A material handling machine as defined in claim 7

wherein said one pivotal interconnection comprises the pivotal interconnection of said hydraulic power means to said boom, and wherein said piston rod is pivotally connected to a link member pivotally connected to said boom, and said additional power means effects movement of said link member to vary the position of the pivotal interconnection of said piston rod and link.

9. A material handling machine as defined in claim 8 wherein said additional power means comprises a hydraulic cylinder pivotally connected to said support adjacent to the boom pivot axis and a piston rod extending from the cylinder and pivotally connected to said link member.
